UNITED STATES PATENT OFFICE.

JOHN R. ANDERSON, OF MOLINE, ILLINOIS.

AMUSEMENT DEVICE.

Application filed October 1, 1925. Serial No. 59,757.

This invention relates to a novel and improved amusement device and more particularly to such a device, which may be used as a teeter and also as a roundabout or merry-go-round. Such devices have been built in the past, as exemplified in the patent to Dickson No. 818,079, but it is to improve upon devices made in accordance with Dickson and other patents known to me that I have made 10 the invention forming the subject matter of this application.

One feature of my invention resides in novel and improved means for supporting a board intermediate its ends upon a pivot 15 in such a manner that the board may rotate about either a horizontal or vertical axis, and so that the horizontal axis shall be disposed a substantial distance above the top of the board. By this arrangement the lever 20 arm measured from the fulcrum formed by the horizontal axis to the seat at the end of the board varies as the board oscillates about its axis. This results in a slowing up or retardation of the end of the board which is 25 rising. This construction is designed to be an improvement over that shown in the patent to Morris No. 1,261,149, because of simplified and more durable construction.

Other objects of my invention are to provide 30 a device of the above character which may be cheaply and efficiently manufactured; which may be easily disassembled so as to be moved from place to place; and which may be readily converted to other purposes.

In the accompanying drawing in which I 35 have shown a selected embodiment of my invention;

Fig. 1 is a side elevation thereof.

Fig. 2 is a section on the line 2—2 of Fig. 1.

Referring now to the drawings in detail, I have shown a stand having a plurality of legs 1 secured together at their upper ends to form a support for a post 2. While the post may be secured to the stand in any suitable manner, I have shown a pair of castings 3 and 4 having apertures for receiving the legs 1 and having the lower reduced portion 5 of the post passing therethrough, this portion being threaded to receive the nut 6 to 45 secure the parts together. As the nut is tightened up it co-acts with the shoulder 7 on the post to securely clamp the legs 1 in position and also to hold the post rigidly upright. 50 The post is rounded at its upper end to form a bearing 8 upon which is supported a

yoke 9 having a portion of its inner surface co-acting with the bearing 8 on the post. It will be seen that this yoke is U shaped, as viewed in Fig. 2 and that the legs of the 60 U are of substantial length so that tipping of the yoke and consequently of the board in a transverse direction is prevented. The yoke is also triangular in form, as viewed in Fig. 1, that is in a direction at right angles 65 to the U shaped section so as to permit rocking on the top of the post in that direction. Obviously also the yoke may rotate freely about a vertical axis.

The yoke is secured as by screws passing 70 through flanges 10 to the top of the board 11, which is provided with a suitable slot 12, the ends 13 of which form a continuation of the inner surfaces 14 of the triangular shaped section of the yoke. In order to support and brace the yoke to better advantage, I provide the brace 15, which may be in the form of a single length of wire and received within a recess 16 in the top of the yoke and which may have its ends bent so as to pass 80 through the board and threaded to receive fastening means 17.

The board is provided adjacent its ends with suitable handles 18, which may be secured to the board in any suitable manner 85 as by brackets 19 and it will be obvious that persons seated on the ends of the board may grasp the handles 18 and then may operate the board in the usual manner as a seesaw or teeter, or may also cause the board to rotate about the vertical axis of the post in the manner of a merry-go-round or roundabout. With an ordinary seesaw the person sitting on the rising end exerts a constantly decreasing leverage because of the fact that 95 the end of the board is passing along the arc of a circle, and consequently the lever arm is being constantly decreased. However, by providing the fulcrum formed between the top of the post 8 and the corresponding 100 bearing on the yoke, a substantial distance above the board, this tendency will be offset to a considerable extent and consequently there will be a tendency to make the operation of the board more uniform.

From the above it will be apparent that I have provided a novel and improved amusement device which is rugged in character and cheaply made, but which may be readily knocked down or set up for transportation from place to place. While I have shown the stand as assembled, it is obvious 105 110

that the legs may be removed from the castings in which they are placed in case it is desired to reduce the space occupied by the device to a still further extent.

5 By placing the yoke on top of the board I obtain maximum height of the fulcrum with less material, and by employing the truss rod 15 bearing on the apex of the yoke above the top of the board the yoke is forced against the board in ratio to the weight on the ends of the board, instead of straining away from the same. Furthermore, by this construction and arrangement of parts there is less liability of the board ever becoming disengaged from its fulcrum.

I am aware that changes in the form, construction and arrangement of parts may be made without departing from the spirit and without sacrificing the advantages of the invention and I reserve the right to make all such changes as fairly fall within the scope of the following claims:

I claim:

1. An amusement device comprising a stand, a post on the same rounded at its upper end to provide a bearing, a board having a longitudinally disposed slot therein to receive the post which projects above the board, and a yoke upon the upper face of the said board, said yoke being U-shaped in cross section in one plane and triangular in cross section in a plane at right angles to the said first-named plane and in the direction of the length of the board. 25

2. An amusement device comprising a 35 board, a yoke secured to the said board upon its upper surface and having a bearing extended through and terminating above said board, and a brace extended in the direction of the length of the board and resting upon the apex of the yoke and having its ends secured to said board upon opposite sides of the yoke. 40

JOHN R. ANDERSON.
